A. R. LAWRENCE.
HEAT INTERCHANGER.
APPLICATION FILED OCT. 16, 1920.

1,429,149.

Patented Sept. 12, 1922.

UNITED STATES PATENT OFFICE.

ALMON R. LAWRENCE, OF QUINCY, MASSACHUSETTS, ASSIGNOR TO ENGINEERING DEVELOPMENT COMPANY, OF BOSTON, MASSACHUSETTS, A CORPORATION OF MASSACHUSETTS.

HEAT INTERCHANGER.

Application filed October 18, 1920. Serial No. 417,605.

To all whom it may concern:

Be it known that I, ALMON R. LAWRENCE, a citizen of the United States, residing at Quincy, in the county of Norfolk and State 5 of Massachusetts, have invented new and useful Improvements in Heat Interchangers, of which the following is a specification.

The present invention relates to heat interchangers of the tubular type wherein liquid is caused to flow through tubes which are surrounded by a fluid medium in an enclosed space (hereinafter referred to as a "receiving chamber") for the purpose of effecting transfer of heat between such 10 medium and liquid when their respective temperatures are different. Such a heat inter changer is exemplified in a surface condenser for steam plant use, having water tubes by which cooling water is conducted 15 through the interior space or chamber of a shell adapted to receive steam. As the invention is principally intended for the uses of steam condensers, and probably has its greatest value in that connection, I will in 20 the following specification explain and describe its characteristics, functions and utility with reference to such a condenser.

It has been observed in the operation of steam condensers of the tubular type as heretofore made, that their efficiency in condensing steam is substantially less than what should be the maximum, having regard to the temperature and quantity of cooling water, the area of cooling surface, and other 25 known factors; and that serious corrosion occurs in the entrance ends of the tubes. I believe that I have discovered the cause of these difficulties; and on my discovery as a basis I have devised a means for overcom- 30 ing such difficulties, by removing the cause thereof, which has been proved by practical experience to be effective for the purpose.

As being helpful to an understanding of the characteristics and utility of the invention, I will first state the essentials of my discovery as follows.

The cooling water used in a condenser is first delivered to a chamber at one end of the condenser shell, into which chamber the tubes open through a tube sheet which par-

titions off the chamber from the steam space of the condenser. The stream of water in passing from the chamber, where it exists under pressure, into the tubes, wherein the pressure is less, contracts to a diameter less 55 than that of the tube near the entrance end of the latter, following the known law of flow of liquids through an orifice. After contracting to its minimum diameter, the water jet expands and fills the tube; but 60 where the contraction occurs, there is an open space between the jet and the surrounding part of the tube, wherein a partial vacuum exists. Oxygen and other gases carried by the water are caused by the vacuum 65 to occupy the space within the tube around the contracted jet, and the gas accumulation retards the velocity of the jet, causes or tends to cause eddies in the water, corrodes the tube, and impedes heat conduction. 70

The invention which I am about to describe in detail and claim consists in a means for preventing the formation of a vacuum or gas pocket between the contracted jet of water and the surrounding walls of the tube. 75 This means may be embodied in a variety of forms, each involving a constriction of the interior of the tube, on lines conforming to the contraction curve of liquid flowing through an orifice to less than the diameter of its entrance orifice in that part of the tube where the contraction of the jet occurs, that is, at or near the entrance of the tube. Such constriction is best accomplished by adding or applying a separate piece hav- 80 ing a bore which is so designed as to produce the desired constriction, and may also be accomplished by suitably shaping the tube itself. The drawings herewith furnished illustrate graphically some of the possible 85 modes and forms in which the invention involved in a constricted tube adapted for heat interchange between fluids may be embodied.

In the drawings, Figure 1 is a sectional view of a surface condenser to illustrate the application of the invention in one of the environments for which it is particularly designed and in which it has especial utility.

Figure 2 is a sectional view enlarged of 100

the entrance end of a tube, such as a condenser tube, equipped with one specific form or embodiment of the invention.

Figure 3 is a similar view of another form or embodiment of the invention.

Figure 4 is a similar view of a further form of the invention.

Like reference characters designate the same parts in all the figures.

10 A typical surface condenser is conventionally shown in Figure 1, the intention in regard thereto being not so much to show a specific heat interchanging apparatus as to illustrate by reference to a species the nature 15 of the apparatus wherein the invention has its special utility. But assuming for the purposes of explanatory description that the apparatus depicted is a steam condenser, the essential parts comprise a shell *a* having 20 heads *b* and *c*, an inlet *d* for steam and an outlet *e* for the condensed water, connections *f* and *g* through the heads for admission and exhaust of cooling water, interior tube sheets *h* and *i*, and tubes *k*. The tube sheets separate the interior of the shell into a central steam space or receiving chamber wherein the external connections *d* and *e* open, and water spaces at the ends into which respectively the connections *f* and *g* open. The 25 tubes are mounted at or adjacent to their ends in the tube sheets in a water and steam tight manner, being conveniently screwed or expanded, or otherwise rigidly secured in one of the tube sheets and having slip joints, 30 through stuffing boxes, with the other of the tube sheets. It may be assumed here that the cooling water enters the right hand water chamber through the connection *f*, and that the tubes have slip joints in the 35 right hand tube sheet *h*. Figure 2 shows in detail one of the types of slip joint and stuffing box used in apparatus of this character. The tube-receiving hole in the tube sheet is of a diameter fitting freely 40 about the tube at the inner side of the sheet, and is enlarged at the outer side and is tapped to receive a threaded gland *l*. Packing *m* is confined between the gland and a shoulder in the hole, and is compressed in a 45 usual manner to make a fluid tight slip joint with the exterior of the tube.

In the condensers heretofore used, where there is no substantial difference between the diameter of the tubes at their entrance ends 50 and at other points, contraction of the jets flowing into the tubes from the water space occurs as explained in the introductory part of this specification, with resulting loss of efficiency. I have overcome the objectionable effects which result from such contraction of the jets by so constricting the tubes 55 that they are entirely filled with the water which passes through, in the part where the jet is contracted, as well as elsewhere.

60 65 The form of constriction embodying my in-

vention which is illustrated in Figure 2, consists of an inserted nozzle *n* which fits the interior of the tube and has a shoulder *o* to limit the distance to which it may enter the tube. The bore of the nozzle is contracted between its ends and is enlarged from the zone of greatest contraction with a smoothly curving flare toward both ends. The mouth or entrance end of this bore is therefore wider than the interior of the nozzle; and the length of the nozzle and the shape of its bore approximate to the shape and length of the contracted section of a jet of liquid flowing from an orifice of the same size as the entrance to the nozzle, under pressure of a head approximately the same as the pressure by which the cooling water is forced through the tubes. Consequently the water flowing into the tube completely fills the bore of the nozzle, and in enlarging after 70 leaving the constricted area of the latter, it completely fills the uniform diameter of the tube throughout its entire length. Thus no opportunity exists for a vacuum to be formed, no eddies occur in the water stream, 75 gas can not collect between the stream and the tube, corrosion in the entrance end of the tube is avoided, the rate of flow of water through the tube is increased, the power required to force the water through the tube 80 is reduced, and the greatest possible efficiency of heat transfer occurs between the water stream and the vapor in the steam space.

When the nozzle is applied to the tube it 100 becomes virtually a part of the tube and forms a constriction or contracted zone of gradually decreasing and then increasing diameter within the mouth of the tube. In the form now being described the constriction is smaller in diameter than any other part of the tube, not only smaller than the entrance orifice or mouth, but also smaller than that part of the tube which the water traverses after leaving the constriction.

105 Sleeves or nozzles equivalent to the nozzle sleeve *n* may be manufactured in sizes and forms appropriate to condensers of various types and capacities operating under various conditions of water pressure and so 110 forth, and may be applied to such condensers already in service as well as to condensers in course of being built. Their application to condensers in service involves no more difficulty than is required to 115 remove the head and apply the nozzles to the tubes then exposed. The inserted nozzles may be held in place by friction or secured in any other suitable manner to prevent their becoming dislodged from any 120 cause, such as the violent movement imparted to marine condensers by the pitching of the vessel in a heavy sea.

125 An example of a nozzle associated with a tube and having the characteristics above 130

defined, with the exception that the nozzle is not actually inserted in the tube and that its least diameter is the same as the bore of the tube, is shown in Figure 4 and designated n' . This nozzle has the same enlarged mouth and the contracted bore, the walls of which change diameter gradually and have the essential relation to the contraction curve of a jet, as already described. This form of nozzle may be secured in the tube sheet, and as a convenient means for mounting it, it may be combined with the gland, whereby it is a combined gland and nozzle. Other modes of attaching or associating the nozzle with the tube will readily occur to those skilled in the art.

The added or inserted nozzle evidently can be applied to condensers already in service without requiring any change in the structure or form of the tubes.

Figure 3 shows the invention embodied in an integral tube k^1 without an inserted or applied nozzle. Here the entrance end k^2 of the tube is extended beyond the tube sheet into the water space, and is enlarged on such lines of curvature that the walls leading from the enlarged orifice to the body of the tube are curved conformably to the contraction curve of a jet flowing under head through said orifice.

It is not to be assumed from the foregoing detailed description that the constriction provided as described must be placed upon that end of the tube which makes a slip joint with the tube sheet, or that the constricted entrance end of the tube must be capable of sliding in the tube sheet. On the contrary the tube may be rigidly fast

at its constricted or entrance end to the adjacent tube sheet, and any necessary relative movement of the tube provided for at its other end.

What I claim and desire to secure by Letters Patent is:—

1. A heat interchanger having a receiving chamber, liquid conducting tubes passing through said chamber, and a liquid chamber into which said tubes open at one end, those ends of the tubes which open into said liquid chamber and into which the liquid is designed to enter having bores which gradually contract in diameter from their entrance orifices and are subsequently enlarged, on longitudinal lines conforming substantially to the contraction and enlargement of a jet of liquid flowing under a head through an orifice into a tube.

2. A heat interchanger having a receiving chamber, liquid conducting tubes passing through said chamber, a liquid chamber into which said tubes open at one end and nozzles fitted in those ends of the tubes which open into said liquid chamber and into which the liquid is designed to enter, said nozzles having bores which diminish from the entrance orifice to a constricted zone smaller in diameter than the bore of the associated tube, on longitudinal smooth curves conforming to the contraction curves of a jet of liquid issuing under pressure from an orifice, and are gradually enlarged from the constricted zone to a diameter approximating the bore of said tube.

In testimony whereof I have affixed my signature.

ALMON R. LAWRENCE.
